UNITED STATES PATENT OFFICE.

JOHN C. MILLER, OF WATERBURY, CONNECTICUT, ASSIGNOR TO THE MATHEWS & WILLARD MANUFACTURING COMPANY, OF SAME PLACE.

DESIGN FOR A BASE FOR LAMPS.

SPECIFICATION forming part of Design No. 23,673, dated October 2, 1894.

Application filed August 24, 1894. Serial No. 521,248. Term of patent 3½ years.

To all whom it may concern:

Be it known that I, JOHN C. MILLER, of Waterbury, in the county of New Haven and State of Connecticut, have invented a new Design for Bases for Lamps; and I do hereby declare the following, when taken in connection with the accompanying drawing, and the letters of reference marked thereon, to be a full, clear, and exact description of the same, and which said drawing constitutes part of this specification, and represents in the figure a perspective view of a base for lamps embodying my design.

My invention relates to a design for bases for lamps, and consists in the configuration and ornamentation as hereinafter described and shown in the accompanying illustration.

The base proper consists of a circular body supported by four legs, each leg terminating

in a shell A. Above the shells A the legs are ornamented by scrolls B and a floriated design C, and terminate in rounded panels D, upon each side of which is a scroll ornamentation E. Between each leg the body is ornamented by a series of ribs F and scrolls G, below which are two parallel bands H. The body is surmounted by a head I, which is ornamented by a series of scroll figures J.

I claim—

The design for a base for lamps, as herein described and shown.

In testimony whereof I have signed this specification in the presence of two subscribing witnesses.

JOHN C. MILLER.
